UNITED STATES PATENT OFFICE.

JESSE L. MAYBERRY, OF NEW YORK, N. Y.

SIGNALING APPARATUS.

1,279,393.

Specification of Letters Patent. Patented Sept. 17, 1918.

Application filed November 30, 1915. Serial No. 64,239.

To all whom it may concern:

Be it known that I, JESSE L. MAYBERRY, a citizen of the United States, and a resident of the city, county, and State of New York, have invented a certain new and useful Improvement in Signaling Apparatus, of which the following is a full, clear, and exact description, reference being had to the accompanying drawings, forming part of this specification.

This invention relates to improvements in signaling apparatus which comprises movable indicators so arranged and capable of being so operated as to enable the driver of an automobile to show by them when he intends to turn to the right or left or to stop, the object of the invention being to render apparatus embodying it better in its mode of operation and less apt to require objectionable care than any similar apparatus heretofore devised. The invention consists of signaling apparatus having the features of construction, the electrical and mechanical parts, and the combinations of devices, which are described below and specified in the claims.

On the accompanying sheets of drawings, on which like reference-numerals designate like parts of different views:

Figure 1 is both a front elevation of parts of apparatus embodying the invention, and a diagrammatic illustration of electrical circuits and switches on which the operation of the apparatus depends.

Fig. 2, a detail of a crank-arm, partly shown in Fig. 1;

Fig. 3, a plan of three electromagnets and other devices which the apparatus includes, two of these magnets being solenoidal magnets;

Fig. 4, an enlarged sectional view of one of the solenoidal magnets;

Fig. 5, a front elevation of the multiple switch diagrammatically illustrated in Fig. 1, the switch being in a case which is shown in section; and

Fig. 6, a top view of this case and the handle of the switch.

The indicators, magnets, and some other parts of the apparatus are supported by an oblong frame which is to be affixed to the back of an automobile and inclosed in a case, having openings so formed and arranged as to enable the indicators to move from their normal positions to others in which they will project from the ends of the case.

The frame is composed of the front and back plates, 1 and 2, and the cross-bars 3. The shafts, 4 and 5, which are rock-shafts, extend through these plates and have bearings in blocks fast on the inner faces of the plates. The indicators 6 and 7 are fast on the shafts 4 and 5 respectively at their rear ends. These indicators are preferably arrows, each having the form of the arrow 6 (Figs. 1 and 3), one of them (6) having on its back the word Right, and the other (7) the word Left. The shaft 5 is tubular and through it extends the small shaft 8, to which is affixed at its rear end the indicator 9, which is an oblong plate a little wider and longer than the arrow 7 and on the back of which is the word Stop. The shafts 5 and 8, which have a common axis, are normally clutched together by means of the disk 10 and latch 11, the disk being fast on the shaft 5 at its front end and the latch surrounding the shaft 8 and being pivoted thereto by pins 12, and having on it at its inner end (the end toward the right of the automobile) a stud 13 which fits in a hole in the disk, the spring 14 tending to keep the latch engaged with the disk. The latch extends outward beyond the disk and has at its outer end the eye 15. The crankarms 16 and 17 are fast on the shafts 4 and 5 respectively and when the indicators are in their normal positions these crankarms extend straight upward from the shafts. Each crankarm has in it, at its swinging-end, a short slot 78 (Fig. 2).

The solenoidal magnets 18 and 19 are pivoted to and between the plates 1 and 2 of the frame, the pivots of the magnet 18 being at the points 20 and those of the magnet 19 at the points 21. The cores 22 and 23 of these magnets are connected to the crankarms 16 and 17 respectively by the pins 24 and 25 which are tight in the cores, extend through the slots 78, and fit loosely in the slots. The coilsprings 26 and 27 surround the cores and bear against the spools of the magnets and against disks fast on the cores, and exert on the crankarms through the cores force enough to hold the arrows 6 and 7 and the sign 9 in their normal positions. The core of each of these magnets closely fits in a non-magnetic tube 28 which may be brass and in which the core acts as does a piston in its cylinder, the tube having the head 29 and the core having in it a non-magnetic plug 30 projecting from its end and forming a stop to limit the inward

movement of the core. In the head 29 are two small apertures. One of these is partly closed by a screw 31, in the stem of which is a groove extending from the head 5 throughout the length of the stem. By this means a vent is provided, the size of which may be varied by turning the screw from its outer end. In the other aperture is a ball 32 which fits against a valve-seat between it 10 and the inner face of the head 29, the ball being loose in the head and being confined between the seat and a pin fixed in the head and extending across the aperture.

The spool of the magnet 33 is attached at 15 its ends to the plates 1 and 2. The core 34 of this magnet passes through the plate 1 and has at its front end a pin 35 formed on or fast in the core, and when the latch 11 is in its normal position the front end of this 20 pin is close to but a little behind the eye 15 of the latch.

The brackets 36 and 37, attached to the front face of the frameplate 1, support two 25 groups of devices which form parts of the electrical circuits and some or all of which are flat springs. The three devices 38, 39 and 40 are fastened by screws to the top of the bracket 36, and each is insulated from the next and from the bracket and screws 30 by non-conducting material represented in Fig. 1 by heavy black lines. The device 40, which is a spring, is normally in contact with a projection on the device 39 near its right end. The latter device may or may 35 not be a spring. To the device 38, which also is a spring, is attached the bar 41 which projects over the shaft 4 and on the under side of this bar is the block 42, the lower face of which is inclined as shown. The pin 40, which is affixed to this bar under the right end of the spring 40, is normally out 40 of contact with the spring but is movable into contact with it by the action on the block 42 as hereinafter described of the pin or cam 45 44 fast on the shaft 4. The devices 45, 46 and 47 on the bracket 37 are similar to those on the other bracket, each of these being insulated from the others and from the bracket and the screws which attach them to it. The bar 48 is fastened to the spring 45, from 50 which it extends over the shaft 5, and on the under side of this bar is a block similar to the block 42, and in the bar is a pin the relation of which to the spring 47 is similar 55 to that of the pin 43 to the spring 40. The pin 49 fixed in the disk 10 and projecting from the back thereof under the block on the bar 48 acts on this block in the operation of the apparatus as hereinafter described.

The case 50 incloses the parts of the apparatus which are supported by the frame, except that in the under side and ends of the case are slots 51 through which the arrows 65 and sign 6, 7 and 9 are movable to positions

in which they project from the ends of the case, as described below. The bands 52, attached to the plate 2 and to the rear wall of the case and extending over the indicators, and the band 53 attached to the plate 1 70 and front wall of the case, hold the frame and case together. On the case are mounted the tail-lamp 54 and the right and left signal-lamps 55 and 56.

The multiple switch comprises a block 57 75 (Fig. 5) of insulating material supporting four groups of spring-contacts. The standard 58, resting on and fastened to this block, has at its upper end the ball 59 (indicated by dotted lines) which fits in a socket in 80 the under side of the four-armed spider 60, having the stem 61 which extends through the top of the case and has at its upper end the handle 62. The top of the switch-case 63 has in it the opening 64, in the four 85 branches of which the upper part of the stem 61 is movable from its normal position to the right, to the left, forward, and backward. The opening 64 is covered by the shield 65, attached to and movable with 90 the stem 61. The arms of the spider, which is of insulating material, extend to the four groups of spring-contacts, one of these being on the right of the standard 58, another on the left thereof, another in front of it, and 95 the other behind it, and each group comprises two springs 66 between which an arm of the spider extends and which so bear on the arm that when its outer end is raised the upper ends of the springs are forced 100 outward. The springs 66 of each group are normally in contact with the springs 67 thereof, and will be forced out of contact with the latter when the handle 62 is moved and the spider so rocked on the standard 105 that the outer end of the arm extending between the springs 66 is raised. The right, left and front groups are all alike, and each of these groups comprises springs 68 which are normally not in contact with the springs 110 66. The springs 66 of each of these groups are forced into contact with the springs 68 of the group by the action of the spider when it forces the springs 66 from the springs 67. The rear group does not include springs 68. 115

In the diagram of Fig. 1 the circle 69 represents the spider and the lines 70 represent the springs 66, other lines representing the other springs of the four groups, as will readily be understood. The wires of the 120 circuits which include the battery 71, and the right, front and left groups of springs of the multiple switch, are shown connected to posts A B C D E F G H, and to posts a b c d e f, some of the wires being also connected 125 to the devices 38, 39, 40, and 45, 46, 47. The circuits which include the windings of the solenoidal magnets pass through the pivots of these magnets. The winding of the magnet 33 is connected to the spring 47 at its 130

right end and to the post H. The rear group of springs of the multiple switch is normally in the circuit which includes the head-lamps 73, battery 74, and switch 75, and parts of 5 which are connected to the resistance-coil 76.

The length and height of the case 50, and those of a common license-plate, are about the same respectively, so that the license-plate 77, which will cover or nearly cover 10 the back of the case, may be attached thereto.

Apparatus like that contained in the case 50, but preferably not including a stop-signal (9), shaft 8, clutch, or magnet such as the magnet 33, for these would be unnecessary and therefore not desirable, may be attached to the front of the automobile and inclosed in a similar case, and on the front of the case may be two signal-lamps like the lamps 55 and 56. The front solenoids and 20 lamps (not shown) would be connected with the posts a, b, c, d, e, f, as the solenoids 18 and 19 and lamps 55 and 56 are connected with the posts A, B, C, D, E, F.

The switch 72 is in the circuit which includes the tail-lamp 54, and to this switch extend wires leading from the other four lamps. At those points close to the switch where the five wires leading from the tail-lamp and four signal-lamps end, there are 30 five contacts all of which are broken when the switch is open. This switch is to be closed only when the lights are needed. When it is open current does not pass through any of the lamps. When it is closed 35 current passes constantly through the tail-lamp 54, going to the lamp from the battery 71 through wires a¹ and a², the post G, and wire a³, and going to the battery from the lamp through wire a⁴, the switch 72, and 40 wires a⁵ and a⁶, but current does not pass through either of the signal-lamps 55 and 56 unless the multiple switch is operated. When the handle 62 of the multiple switch is swung so that the spider acts on the 45 springs 70 of group I, shown at the left of the circle 69 (Fig. 1), and forces these springs into contact with the outermost springs of the group, current goes from the battery 71 through wire a¹ to and over two 50 springs of group II, and thence through wire a⁷ to group I where, if the apparatus includes front as well as rear signals, it divides into two branches, and these branches go over springs 70 of group I and to posts B 55 and b, passing through wires a⁸ and a⁹ respectively. From post B current goes through wire a¹⁰, plate 39, plate 40, wire a¹¹, the solenoid 18, wires a¹² and a¹³, post D, and wire a⁶, to the battery. From post b current 60 goes through wire a¹⁴, plates (not shown) similar to 39 and 40, through the front right solenoid, and wire a¹⁵, to post d, and thence to the battery through wires a¹⁶, a¹⁷ and a⁶. If the apparatus does not include front signals then the current goes from group I to

post B and thence through the solenoid 18 as described, but of course will not go to post b as this will not then be in a circuit. If the switch 72 is closed, a branch of the current goes from post B through wire a¹⁸, to 70 and through lamp 55, through wire a¹⁹, to post A, through wire a²⁰, to switch 72, and thence to the battery through wires a⁵ and a⁶, and if there is a front right signal-lamp a branch of the current goes from b through 75 wire a²¹, to and through that lamp, through wire a²², to post a, through wire a²³, to switch 72, and thence to the battery through wires a⁵ and a⁶. Current will not then pass through any of the other magnets or any of 80 the other signal-lamps.

The magnet 18, thus energized, pulls the crank arm 16 to a horizontal position, and swings the arrow 6 on the axis of the shaft 4 as indicated by Fig. 1, which shows this 85 crank arm, the solenoid and arrow just after the action begins and when the arrow has left its normal position in the case 50. When the pin 24, which connects the core of the solenoid to the crank arm, reaches or nearly 90 reaches the plane containing the axis of the shaft 4 and the pivotal axis of the solenoid, the projection 44 acts on the block 42, forcing the pin 43 against the spring 40 and raising its right end, so that the circuit is 95 broken between the plates 39 and 40. The bar 41, which is connected with the post C by wire a²⁴, is not then connected with the battery because the wire a²⁵ leading from that post to the multiple switch is connected 100 to the spring which is next to and in front of the rear spring 70 of group I and these springs are not then in contact, so that, although springs 70 of group I are connected with the battery, current cannot pass to wire 105 a²⁵ through springs of that group. As the circuit passing through the solenoid is thus broken, the spring 26 forces the core of the solenoid outward, the momentum of the arrow 6 and other parts continuing the 110 movement of the crank-arm 16 while the pin 24 is moving from end to end of the slot 78 in the crank arm and passing from side to side of the aforesaid plane, and the movement of the arrow is continued by the action 115 of the spring 26 until the arrow extends horizontally outward from the end of the case 50, and there it will be held by the spring until the handle of the multiple switch is again moved. The arrow, pointing 120 to the right, and having on the back the word Right, plainly visible from behind either in daylight or the light thrown on it by the lamp 55 at night, indicates an intention of the driver of the automobile to turn 125 to the right. It will be seen that the circuit which includes the lamp 55 is not broken when the solenoid is deenergized as described.

When the handle of the multiple switch 130

is restored to its normal position, current goes from battery 71 to group II, thence to group I, and thence to post C through wire a^{25} , and a branch goes to post c through wire a^{26} if there are also front signals, and from C current goes through wire a^{24} , to spring 38 and through this spring, bar 41, pin 43, spring 40, wire a^{11} , the solenoid 18, and wires a^{12} and a^{13} , to post D, and thence 10 to the battery through wire a^6 . Thereupon the lower end of the crankarm is drawn upward by the energized solenoid 18 until the pin 24 is between or nearly between the pivotal axis of the solenoid and that of the 15 crankarm and arrow, when the projection 44 leaves the block 42, and the spring 40 returns to its normal position, again making contact with the plate 39. By this action the circuit passing through the solenoid is 20 broken. The momentum of the arrow and other parts continues the movement of the arrow until the pin 24 reaches the inner end of the slot 78 in the crankarm and passes from between the pivotal axes of the solenoid and shaft 4, and then the spring 26 25 forces the arrow to its normal position and there holds it. The circuit which includes the lamp 55 is broken when the handle of the multiple switch is restored to its normal 30 position, for the springs 70 of group I of that switch then move away from the front and rear springs of the group.

From the foregoing description it will be understood that when the handle of the multiple switch is moved so as to force outward the springs 70 of group I, a front right solenoid (not shown) would be energized as is the solenoid 18, and a front right arrow or similar indicator (not shown) would be 35 thrown out as is the arrow 6, and current would pass through a front right signal-lamp (not shown), that when the handle is restored to its normal position the solenoid would be energized, the arrow would be returned to within the case, and the circuit including the lamp would be broken, and that 40 during the outward movement of the arrow, and during its return, the circuit including the solenoid would be broken by the action on it of the solenoid, and the 45 spring surrounding the core of the solenoid enabled to continue and complete the movement of the arrow. The front solenoid will be energized to impart the inward movement 50 to the arrow, by current passing from post c to the battery through wire a^{27} , devices like spring 38, bar 41, pin 43, and spring 40, above described, and through the solenoid, wire a^{15} , post d , and wires a^{16} , a^{17} and a^6 . 55 A movement of the handle of the multiple switch so that the springs 70 of group III will be forced into contact with the front and rear springs of the group, will enable current to pass from the battery 71 through 60 wire a^1 , to and over two of the springs of

group II, through wire a^{28} , to springs 70 of group III, and thence, if there is a front left signal (not shown), over the front and rear springs of group III, and to posts F and f through wires a^{29} and a^{30} respectively. 70 From post F a branch of the current will go through wire a^{31} , to lamp 56, through wire a^{32} , to and over switch 72, and thence to the battery through wires a^5 and a^6 . Another branch, starting at post F, will go 75 through wire a^{37} , plates 46 and 47, wires a^{38} and a^{39} , the solenoid 19, wires a^{40} and a^{13} , and to post D, from which it will go to the battery through wire a^6 , and another branch, starting near the spring or plate 47, will go 80 through wire a^{38} , the magnet 33, wire a^{41} , to post H, thence through wire a^{42} , to and over two springs of group II, and thence to the battery through wires a^{17} and a^6 . Hence the battery will then energize both the 85 solenoid 19 and the magnet 33, and will light the lamp 56. The magnet 33 will draw backward the eye of the latch 11 so that the latch will be disengaged from the disk 10 and the eye will surround the pin 35 on 90 the core of the magnet, and then the shaft 8 will be locked to the magnet and be prevented by the latter and the latch from turning. By this means the sign 9 will be held in its normal position during the 95 action of the solenoid 19. The solenoid will draw the crankarm 17 to about a horizontal position, the circuit including the solenoid will be broken by the action of pin 49 on the block attached to the under side of bar 100 48, and by the action on the spring 47 of the upwardly projecting pin on the bar 48, and the spring 27 will act on the crankarm and continue and complete its movement. The 105 breaking of the circuit in this operation during the outward movement of the arrow 7, deenergizes the magnet 33 as well as the solenoid but the latch will be kept engaged with the pin 35 of the magnet by the action of the stud 13 on the front face of the disk. 110 The return of the handle of the switch to its normal position will enable current to go through wire a^1 , group II, wire a^{28} , group III, and wire a^{43} to the post E, then through wire a^{44} , spring 45, spring 47, and 115 spring 47, one going through wires a^{38} and a^{39} , the solenoid, wires a^{40} and a^{13} , post D and wire a^6 , and the other going through wire a^{38} , magnet 33, wire a^{41} , post H, wire 120 a^{42} , group II, and wires a^{17} and a^6 . Then the energized solenoid will draw the crankarm back to the horizontal position, the circuit will be broken, and the spring 27 will 125 complete the movement of the crankarm, shaft and arrow. As soon as they reach their normal positions the stud 13 of the latch 11 will be forced by the spring 14 into the hole in the disk 10 so that the shafts 5 and 8 will be clutched together again. 130

If the apparatus should include a front left signal (not shown), but not a sign 9, the front solenoid would be energized in this operation, first by current passing from post 5 f through wire a^{45} to and through the solenoid, through wire a^{45} , to post d , and thence to the battery through wires a^{16} , a^{17} and a^6 , and afterward, to start the arrow on its return (when the handle of the switch is 10 thrown back to its normal position), by current passing through wire a^1 , group II, wire a^{28} , group III, wire a^{46} , post e , wire a^{47} , the front solenoid, wire a^{16} , post d , and thence to the battery through wires a^{16} , a^{17} and a^6 . 15 The action on the arrow by the solenoid and actuating spring, and the operation of the circuit-breaking means during the outward and inward movements of the arrow, will be such as have been described. The circuit including the front signal-lamp (not shown) 20 will go from post f to the lamp, and thence to wire a^{48} , to switch 72, and to the battery.

When, with a movement of the handle of the multiple switch, the springs 70 of group 25 II are forced into contact with those at the sides of the group, current goes through wire a^1 , two springs of this group, wires a^{49} and a^{29} , to post F, to plate 46, to plate 47, to and through solenoid 19, to post D, and thence to the battery. If switch 72 is closed 30 current also goes from post F through lamp 56. Current does not go through magnet 33 in this operation for the line leading from post H, wire a^{42} and springs of group II then ends in that spring of group II which 35 is not connected at its lower end with any wire. The energized magnet 19, acting as described, turns both shaft 5 and shaft 8, then clutched together, and when the movement of the crankarm is completed by the 40 action of the spring 27, both sign 9 and arrow 7 project from the end of the case, but only sign 9 can be seen from behind for the arrow is hidden by it. The arrow and sign 45 are moved back to their normal positions by the above-described action of the solenoid and spring 27 on the crankarm 17 when the handle of the multiple switch is restored to its normal position, and then the circuit 50 which lights the lamp 56 is broken. In this operation current does not go to the front left solenoid or lamp.

The fourth movement of the handle of the multiple switch from its normal position breaks the circuit normally passing through group IV and the head-lamps 73, when switch 75 is closed. By this means the current may be forced to traverse the resistance-coil 76 so as to diminish the lights of the 55 lamps.

During the inward movement of the core of any of the solenoidal magnets, air is expelled from the tube 28 through the apertures in the head 29, and when the core is forced outward by the spring which acts 60

thereon the ball is pressed by the outer air against the valve-seat so that air cannot enter the tube except by passing behind the ball or through the vent or between the core and tube at the opposite end of the tube. 70 The size of the vent readily can be made such as to prevent the spring from acting too suddenly or forcibly on the crankarm and indicator or indicators connected therewith. 75

But very little current is used at each operation of the apparatus, no matter how long a signal may be exposed, especially when current does not pass through any of the signal-lamps, and it is feasible to use in 80 the apparatus described a current which would burn out or soon destroy a solenoidal magnet if it were to pass through it for more than an instant.

The multiple switch and circuit wires are 85 preferably to be so arranged that when the handle is thrown toward the right of the car the right signals will be operated, when it is thrown toward the left of the car the left signals will be operated, when it is 90 thrown backward the stop-signal will be operated, and when it is thrown forward the head-lights will be made dim.

It will be understood that the invention 95 may be embodied in apparatus differing more or less in form and details from that which has been described.

Having thus described my invention, what I claim as new and desire to secure by Letters Patent, is:

1. Signaling apparatus comprising a movable signaling device, a solenoidal magnet effective to impart motion thereto, circuit-breaking means operative by the magnet, and a spring which acts on the device after 105 the circuit-breaking means operates, the spring being subject to stress through the action of the magnet thereon and being effective to continue the movement of the device after the circuit-breaking means operates. 110

2. Signaling apparatus comprising a movable signaling device, a solenoidal magnet effective to impart motion thereto, circuit-breaking means operative by the magnet, a 115 spring which acts on the device after the circuit-breaking means operates, and a circuit-closing switch operative by hand and effective to close the circuit when the spring is acting on the device. 120

3. Signaling-apparatus comprising a signaling-device movable to and from a visible position, a solenoidal magnet, a current-generator, conductors, a hand-operated switch, and circuit-breaking means operated by the magnet at the end of each inward movement of the core, the magnet being connected with the signaling-device and being effective to move it by successive actions from its normal position and from its visible position. 125

sition, those actions being controlled by different movements of the handle of the switch.

4. Signaling-apparatus comprising a sig-

- 5 naling-device movable to and from a visible position, a solenoidal magnet, a spring effective whenever the magnet is deenergized to force the core outward and to hold it at the end of its outward movement, a current-generator, conductors, a hand-operated switch, and circuit-breaking means operated by the magnet at the end of each inward movement of the core, the magnet being connected with the signaling-device and being effective to move it by successive actions from its normal position and from said visible position, those actions being controlled by different movements of the handle of the switch.

5. Signaling-apparatus comprising a rock-

- 20 shaft, a crank-arm thereon, a signaling-device on the rock-shaft, a solenoidal magnet, a current-generator, conductors, a hand-operated switch, and circuit-breaking means operated by the magnet at the end of each inward movement of the core, the magnet being connected to the crank-arm and being effective to turn the rock-shaft and signaling-device by successive actions in different directions, those actions being controlled by 30 different movements of the handle of the switch.

6. Signaling-apparatus comprising a rock-shaft, a crank-arm thereon, a signaling-device on the rock-shaft, a solenoidal magnet, a

- 35 current-generator, conductors, a hand-operated switch, and circuit-breaking means including a projection on the rock-shaft and a spring-supported block to and from which said projection is movable as the shaft rocks, 40 the magnet being connected to the crank-arm and being effective to turn the rock-shaft and signaling-device by successive actions in different directions, those actions being controlled by different movements of the handle of the switch.

7. Apparatus comprising a movable signa-

- 50 lizing device, actuating means including an angularly movable solenoidal magnet, said device having a crankarm and the core of the magnet being connected at its outer end to the swinging end of the crankarm, the pivotal axes of the crankarm and magnet being parallel and the connected ends of the crankarm and core being movable from side to side of the plane containing those axes, and circuit-breaking means operative by the magnet as the connected ends of the crankarm and core pass said plane.

8. Apparatus comprising a movable signa-

- 60 lizing device, an angularly movable solenoidal magnet, said device having a crank-arm and the core of the magnet being connected at its outer end to the swinging end of the crankarm, the pivotal axes of the crankarm and magnet being parallel and

the connected ends of the crankarm and core being movable from side to side of the plane containing those axes, circuit-breaking means including a part movable in opposite directions with the device by the magnet 70 and arranged to act on the circuit when the connected ends of the crankarm and core pass said plane, and a spring effective to continue the movement of the device after the operation of the circuit-breaking means, 75 the apparatus including a switch operative by hand to close the circuit when the device is in its normal position and when it is in the other position in which it also rests.

9. Apparatus comprising a movable signa-

- naling device, an angularly movable solenoidal magnet, said device having a crank-arm and the core of the magnet being connected at its outer end to the swinging end of the crankarm by a pin attached to one 85 part and passing through a slot in the other, the pivotal axes of the crankarm and magnet being parallel and the connected ends of the crank arm and core being movable from side to side of the plane containing those 90 axes, circuit-breaking means operative by the magnet at the connected ends of the crankarm and core pass said plane, and a spring effective to continue the movement of the device after the operation of the cir- 95 cuit-breaking means.

10. Signaling apparatus comprising two movable signaling devices, actuating means including a solenoidal magnet connected to one of them, a clutch effective to hold them 100 together, and a magnet effective to move one member of the clutch from its normal position.

11. Signaling apparatus comprising two angularly movable and coaxial signaling de- 105 vices, actuating means including a solenoidal magnet, one of said devices having a crank-arm and the core of the magnet being connected to the crankarm, a clutch effective to hold said devices together, and a magnet ef- 110 fective to move one member of the clutch from its normal position.

12. Signaling apparatus comprising two signaling devices each including a rockshaft, 115 actuating means including a solenoidal magnet, one of the rockshafts being hollow and surrounding the other and having a crank-arm and the core of the magnet being connected to the crankarm, a clutch-member fast on the outer shaft, a coacting spring-pressed clutch-member pivotally attached to a projecting part of the inner shaft, and a magnet effective to move the latter clutch-member from its normal position.

13. Signaling apparatus comprising two 125 signaling devices each including a rockshaft, actuating means including a solenoidal magnet, one of the rockshafts being hollow and surrounding the other and having a crank-arm and the core of the magnet being con- 130

connected to the crankarm, a clutch-member fast on the outer shaft, a coacting spring-pressed clutch-member pivotally attached to a projecting part of the inner shaft, and a magnet effective to move the latter clutch-member from its normal position, this member including an arm and the core of the magnet and this arm having interlocking parts.

14. Signaling apparatus comprising an oblong case, three oblong indicators normally confined in the case and pivotally sup-

ported therein, two of these having a common pivotal axis and this axis and that of the other indicator being near the ends of the case and in a plane below the top, and the case having at its ends and under side openings forming passageways through which the indicators are movable to positions in which they project from the ends of the case. 15
